[57] CLAIM

The ornamental design for a spoke design for an automotive vehicle wheel, as shown and described.

DESCRIPTION

FIG. 1 is a side perspective view of my new spoke design for an automotive vehicle wheel; and,
FIG. 2 is a front elevational view of the design of FIG. 1.
The broken lines shown in FIGS. 1 and 2 of the drawing are for illustrative purposes only and the subject matter depicted thereby constitutes no part of the claimed design.
